UNITED STATES PATENT OFFICE.

JAMES P. SNEDDON, OF BARBERTON, OHIO, ASSIGNOR TO THE BABCOCK & WILCOX COMPANY, OF NEW YORK, N. Y., A CORPORATION OF NEW JERSEY.

SUPERHEATER-BOILER.

973,717.

Specification of Letters Patent. Patented Oct. 25, 1910.

Application filed February 19, 1907. Serial No. 358,170.

To all whom it may concern:

Be it known that I, JAMES P. SNEDDON, of Barberton, Summit county, Ohio, have invented a new and useful Superheater-
5 Boiler, of which the following is a full, clear, and exact description, reference being had to the accompanying drawings, forming part of this specification.

In the drawing I have shown a sectional 10 side elevation of one form of my improved superheater boiler.

My invention relates to the class of superheater boilers, and more especially to that type wherein the gases flow in up and down 15 passes over successive sets of water tubes connecting upper and lower transverse drums.

The object of the invention is to provide 20 a simple, cheap and efficient superheater boiler of this type, in which the degree of superheat may be varied by varying the path of the gases over the superheating tubes.

A further object of the invention is to 25 combine the U-shaped superheater with a boiler of this type, wherein the superheater occupies a pass of its own between any suitable baffles, with water-heating surface between it and the source of heat.

30 In the drawing, 2 and 3 represent upper transverse steam and water drums, connected by banks of tubes 4 and 5 with a transverse mud drum 6. The flame and gases arising from the furnace 7 are directed 35 up among the tubes 4 by the rear baffle 8, and thence flow down between such baffle and the baffle 9 and rise among the tubes 5 to their upper ends and then pass over the top of baffle 10 to the outlet flue 11.

40 In the second pass for the gases between the baffles 8 and 9, I provide the superheater, which in this form consists of U-shaped tubes 12 connecting the upper boxes 13 and 14 placed in the roof of the setting. These 45 boxes extend transversely of the setting, and the box 13 is connected with the steam space of the drum 3 by a pipe 15, the outlet pipe 16 for the superheated steam being connected to the other box 14. In this form 50 the superheater is placed in the rear portion of the V-shaped space between the baffles 8 and 9, and at the upper part of the baffle 8 I place the pivoted adjustable baffle shelf 17 having operating chain 18 leading up 55 through the roof to a drum on the shaft of

chain pulley 19. This chain pulley is provided with an endless operating chain 20 which hangs down within reach of the operator; and by it he may adjust the position of the shelf 17 to allow the gases to short-circuit more or less over the superheater tubes, thus changing the amount of superheat. In the form of boiler shown, the drums 2 and 3 are connected by water circulators 21 and by steam circulators 22, 60 steam passing from drum 2 back to drum 3, and then entering the superheater.

The advantages of my invention result from the location of the U-shaped superheater, from the means for adjusting the degree of superheat while the boiler is operated, and the compactness and efficiency of the construction.

Changes may be made in the form and arrangement of the boiler, the position of the superheater, the means for varying the path 75 of the gases, &c., without departing from my invention.

I claim:

1. The combination with a boiler of the transverse drum, multiple bank, serial pass type, of a superheater, constituting the entire heating surface of the second pass, and an adjustable baffle shelf adjacent the bottom of the entrance to the pass arranged to vary the flow of the gases over the superheater; substantially as described.

2. A superheater boiler of the transverse drum, multiple bank, serial pass type, having the superheater located in a pass in the rear of the first pass, and in the normal path of the gases, and an adjustable baffle adjacent the bottom of the entrance to the pass arranged in the pass with the superheater to vary the flow of the gases over the superheater tubes; substantially as described.

3. The combination with a boiler of the transverse drum, multiple bank, serial pass, type, having a triangular shaped pass in the rear of the first pass, a superheater set in said triangular shaped pass, and a swinging baffle in front of the superheater in the normal path of the gases in said pass and at the bottom of the entrance to the pass, and external means for adjusting the swinging baffle during the operation of the boiler; substantially as described.

4. In a boiler of the transverse drum, multiple bank, upright serial pass type, a superheater in one of the passes, and an adjust-

able baffle having a connection extending to a point outside the boiler, the superheater and baffle being in the normal path of the gaseous flow in the same pass and the baffle 5 being located at the bottom of the entrance to the pass; substantially as described.

5. The combination with a boiler of the transverse drum, multiple bank, serial pass, type, of a superheater in a pass back of the 10 first pass and in the normal flow of the gases, said superheater consisting of verti-

cally extending tubes connected to boxes located at the roof of the setting, and means at the entrance to the pass for varying the flow of the gases over the superheater; substantially as described. 15

In testimony whereof, I have hereunto set my hand.

JAMES P. SNEDDON.
